POURING NOZZLE

Herbert Wainwright, Baldwin, N. Y., assignor to
 National Seal Corporation, Brooklyn, N. Y., a
 corporation of New York

Application March 11, 1939, Serial No. 261,171

2 Claims. (Cl. 221—11)

My invention relates to pouring nozzles for directing the flow of liquids from the discharge openings of containers or receptacles, and is particularly adapted for use with pouring nozzles having a plurality of spaced-apart projecting pouring lips, such nozzles to be affixed to the tops of sheet-metal cans.

The objects of my invention are, among other things, to provide a pouring nozzle of this type stamped to the required size and shape out of sheet metal, with multiple pouring lips so that the nozzle itself does not have to be located in a given relationship to the shape of the can in order to pour the contents properly. According to one aspect of my invention, the pouring nozzle may be placed in any position on the top of the can, and there will always be a pouring lip in correct position for use.

Furthermore my improved nozzle with the multiple pouring lips embodies coacting holding or locking means for the closure cap which means are not a part of the pouring lips. This factor is important since the flange of the pouring lip where the liquid leaves the nozzle should be as thin as possible to prevent dripping, and it has been found in pouring nozzles where the lips over which the liquid passes, and such lips are a part of, or integral with, the cap-locking devices, that it is impossible to cause the liquid to pour therefrom in a satisfactory manner.

According to my invention, the flange of the nozzle acts as a sealing surface with the crown of the cap and also cuts off the flow of the liquid when the pouring ceases, while it is entirely separate from the cap-locking means carried by the neck of the nozzle below and inside the pouring lips and inside the flow of the pouring stream.

A further object of my invention is the provision of a multiple lip nozzle that will be cheap to construct and of easy manipulation without instructions, and that will be compact and of pleasing appearance.

Other objects and advantages will be set forth in the following description, which taken with the drawing discloses a preferred embodiment of my improved pouring nozzle and cap.

Of the drawing, Fig. 1 is a side elevation of a can provided with pouring nozzle and closure cap;

Fig. 2 is a top plan view of the nozzle affixed to the top of the can;

Fig. 3 is a sectional view taken on the line 3—3 of Fig. 2;

Fig. 4 is a side elevation of the parts shown in Fig. 2;

Fig. 5 is a top plan view of the nozzle with the cap in place, the cap being partly broken away to show the locking means for the cap on the nozzle; and

Fig. 6 is a sectional view taken on the line 6—6 of Fig. 5.

Similar numerals refer to similar parts throughout the several figures.

Referring to Fig. 1, the can or container 7 is of any usual or preferred construction having the top 8 from which the nozzle 9 extends upwardly with the cap 10 secured to the nozzle 9. As shown in Fig. 3, the nozzle 9 has the cylindrical neck 11 which is fitted to the upturned flange 12 formed in the can top 8 and secured thereto by any suitable means such as the solder 13.

Referring to Figs. 2-6, the nozzle 9 has three pouring lips 14 equally spaced-apart above the neck 11 which lips are similar in structure, and a description of one of such lips will suffice for the others. My invention is not to be limited to three such lips as two or more may be used to suit the requirement.

The lips 14 comprise parts of the sealing flange 15 of irregular contour as shown in Figs. 2 and 5 that is flat and formed with a thin edge. Such flange 15 is concentric with the neck 11 between the pouring lips 14, as shown, but projects outwardly at 16 around and outside the lateral pouring recesses 17 at the pouring points of the nozzle. These recesses 17 are outwardly drawn from the sheet-metal forming upper enlarged portion of the neck 11 (Figs. 3 and 4), with their under surfaces substantially flat to form lugs 18 on the nozzle to be engaged by the locking means of the cap. As shown in Figs. 3, 4 and 6, the sealing flange 15 lies in a horizontal plane throughout the periphery of the nozzle 9 with a thin outer edge.

The cap 10 has the crown 19 and cylindrical depending skirt 20 from the lower rim of which are integral spaced-apart inturned locking lugs 21 in number and arrangement corresponding to the number and arrangement of pouring recesses 17.

In the drawing three inturned lugs 21 are shown which are adapted to engage the nozzle lugs 18 when the cap 10 is twisted into locking position (Figs. 5 and 6). Beneath the crown 19 is the sealing gasket 22 that engages the flange 15 (Fig. 6) when the cap 10 is drawn down on the nozzle 9 as the lugs 21 slide beneath the nozzle lugs 18 as shown in Fig. 6 whereby the gasket 22 effectively seals the entire surface of the flange 15.

In use, the cap 10 is reversely twisted to dis-

engage the cap lugs 21 from the nozzle lugs 18 so that the cap lugs 21 are in alinement with the spaces between the pouring lips 14; then the cap 10 may be lifted and removed from the nozzle 9. As shown in Fig. 2, the user may tilt the can 7 in any convenient way to allow the liquid to be poured from any of the three pouring lips 14, the shape of which in conjunction with the recesses 17 confines the flow without any undesired lateral edge for the stream. In any case the flange 15 overhangs the locking lugs 18 in such a way that adhesive liquids such as varnish, glue or syrup can not drip down on the lugs 18 to cause the cap 10 to seize or freeze on the nozzle, which is important to preclude unintentional locking of the cap to the nozzle.

In my improved multiple lip nozzle there is no strain on the sealing flange 15 when the cap 10 is screwed home as is the case when one lip is used and the cap lugs engage the under side of the pouring lip proper thereby causing the lip to buckle and produce a faulty closure when the cap is screwed into place.

Furthermore it will be observed that the nozzle neck 11 is so formed as to allow an innerseal to be wedged into position on the flange 12 in such position that such seal can not be removed without destroying same.

While I have shown and described a preferred form of my improved pouring nozzle, many changes or modifications may be made in the form and arrangement of the structural parts

without departing from the principles of my invention or sacrificing its advantages.

I claim as my invention:

1. In a pouring nozzle, a cylindrical neck, 5 adapted to be affixed to the top of a container, the upper portion of the neck being enlarged and having a plurality of outwardly extending recesses having convex, vertically-disposed contours and substantially horizontal flat under surfaces formed therein, and a flat sealing surface of irregular contour lying in a single plane superposed around the top of the neck and recesses, the parts of said surface in alinement with the recesses forming multiple pouring lips 10 having outwardly disposed flat curved edges outside the zone of said recesses.

2. In a pouring nozzle, a cylindrical neck having an enlarged upper portion provided with spaced-apart outwardly extending recesses having convex, vertically-disposed contours and substantially horizontal flat under surfaces, and a flat sealing surface of irregular contour and substantially uniform width lying in a single plane surrounding the top of the neck and recesses, the parts of said sealing surface in alinement with said recesses forming pouring lips having flat curved edges outwardly projecting from the irregular contour of said sealing surface with the plane of said lips coinciding with that of the sealing surface.

HERBERT WAINWRIGHT.
